UNITED STATES PATENT OFFICE.

HERMAN ELSAS, OF NEW YORK, N. Y., ASSIGNOR TO PUBLIC SERVICE CUP COMPANY,
OF BROOKLYN, NEW YORK, A CORPORATION OF NEW YORK.

CUP-DISPENSER.

1,318,317.

Specification of Letters Patent.

Patented Oct. 7, 1919

Application filed November 22, 1915. Serial No. 62,738.

To all whom it may concern:

Be it known that I, HERMAN ELSAS, a citizen of the United States, and a resident of New York, in the county of New York and State of New York, have invented certain new and useful Improvements in Cup-Dispensers, of which the following is a specification.

This invention relates to and has for an object to provide mechanism in a cup dispenser for advancing a cup into position readily accessible by the operator upon opening a cover or lid.

The cups, preferably arranged in a nested stack, are carried by an elevator which is advanced one cup distance at each opening and closing of the cover. Mechanism is also provided whereby upon reaching a predetermined height the elevator disconnects the advancing mechanism.

In the drawings accompanying this specification one practicable embodiment of my invention is illustrated. In which drawings—

Figure 1 shows in side elevation the improved mechanism mounted in a housing shown in vertical section.

Fig. 2 shows a front elevation of the same, also in section, the elevator being shown at a different height.

Fig. 3 is a horizontal sectional view taken on line 3—3 of Fig. 1 looking downwardly.

Fig. 4 is a detail of portions of the elevator actuating mechanism in the positions assumed when the cover is partly raised, and

Fig. 5 is a similar view showing the cover down and the pawl held from engagement with the ratchet by the action of the elevator.

The supply of cups and the operative mechanism are preferably mounted in a housing 7 provided with a cover or lid 8 hinged to the housing at what for convenience will be termed the back of the housing. A glass panel 9 may be provided at the front of the housing for the purpose of displaying the cups. Brackets 10 indicate securing or attaching means for mounting the dispenser in some suitable manner, as for instance on a wall or a water cooler.

The cover 8 is shown longer at its front

than at its rear, the side edges being obliquely disposed. The body of the housing is shown provided at its top with a plate or shelf 11 also obliquely disposed, and slanting from the back toward the front. This shelf is shown provided with a central opening 12 of suitable size to permit the passage of the cups. Normally the uppermost cup 13 of the stack of cups 13 extends through such opening 12 in the shelf 11.

Upon opening the cover the uppermost cup is automatically placed in a convenient position to be removed by the operator, and the shelf slanting toward him induces him to move the cup at a slight angle to the axis of the stack thereby freeing the cup from the next one below and at the same time snapping the rear edge of the cup flange past the free end of yieldable detent member 30, thus assuring the delivery of a single cup. The stack of nested cups is shown carried by an elevator 14 mounted in the housing. The closing and opening of the cover actuates the elevator in the following manner in the illustrative example shown in the drawings.

Sprocket wheels 15 are mounted on studs at each side of the top of the housing for carrying endless chains 16 running over sprocket wheels 17 fast on a shaft 18 at the bottom. The elevator is secured to the chains. In the illustration slits 19 are provided in the elevator for detachably engaging the wire links of the chain. Suitable guides for the elevator and the stack of cups are shown in the form of four rods 20.

The elevator is advanced step by step in steps of cup distances at each lifting of the cover, by means of a pawl 21 suitably connected to the cover and a ratchet wheel 22 fast on the shaft 18. A dog 23 is shown for preventing reverse rotation of the shaft. This dog however is fast with a releasing device 31 located at some convenient position so that the attendant upon replenishing the cups may return the elevator from whatever position of advance it may occupy to its lowermost position to enable the supplying of a full charge of cups. The pawl 21 is shown formed by punching a slot in the end of a flat strip bent at right angles about

its longitudinal axis. The portion 21¹ of the pawl is drawn toward a fulcrum 24 by means of a spring 25, located in such position relatively to the ratchet and the cover connection 32 that the pawl is drawn away from the ratchet and out of connection therewith after the amount of movement of the cover has taken place to rotate the ratchet a sufficient distance to effect an elevator advance of one cup distance. Movements of the cover beyond that required for advancing the elevator are idle in so far as the actuating devices are concerned.

The utility of this arrangement of the mechanism is obvious when it is considered that different individuals move the lid different distances, some as far as it will go and others barely far enough to permit the removal of the cup. The result of communicating such irregularities to the elevator is apparent.

It is very desirable that the repeated opening of the cover after the supply of cups is exhausted shall not continue to advance the elevator. Actuator disconnecting mechanism is provided. This in the illustration is a bell crank lever 26 pivoted near the lower or ratchet engaging end of the pawl and having one end 26¹ in position to engage the pawl upon the elevation of the other end. The end 26² being shown connected to a link 27 carrying a pin 28 located in the path of movement of the elevator adjacent the limit of its upward travel. A spring 29 holds the bell crank 26 at its normal position. These parts are so proportioned that the elevator remains at its position for delivering or dispensing the last or lowermost cup of the stack upon arriving at such position until released and returned by the attendant.

The sprocket wheels 15 are shown located toward the back of the housing and in the angle below the shelf 11 so that the elevator is permitted to rise almost to the horizontal plane of the front of the body of the housing.

Changes can be made within the scope of the claims without departing from the spirit 50 of the invention.

I claim:

1. In a cup dispenser, the combination of an elevator adapted to carry a stack of nested cups, means for actuating said elevator, and 55 means controlled by the elevator for disengaging the elevator actuating means at a predetermined point in the movement of the elevator.

In a cup dispenser, the combination 60 with a housing provided with a hinged lid, of an elevator located therein and adapted to carry a stack of nested cups, means for advancing the elevator step by step embodying a ratchet wheel, a pawl carried by the

lid for engaging and rotating the ratchet 65 wheel, and means controlled by said elevator for disengaging the pawl from the ratchet wheel.

3. In a cup dispenser, the combination with a housing provided with a hinged lid, 70 of an elevator located therein and adapted to carry a stack of nested cups, means for advancing the elevator step by step embodying a ratchet wheel, a pawl carried by the lid for engaging and rotating the 75 ratchet wheel, and means for disconnecting the pawl and ratchet upon a predetermined amount of lid movements.

4. In a cup dispenser, the combination with a housing having at its upper part a 80 shelf slanting from the back toward the front and provided with an opening adapted to permit the passage of a cup, and a lid hinged to the rear of the housing for covering such opening and a cup protruding 85 through the same, of an elevator located in the housing and adapted to carry a stack of nested cups, elevator advancing means embodying a ratchet wheel, and a pawl carried by the lid for engaging and rotating 90 the ratchet wheel.

5. In a cup dispenser, the combination with a housing having at its upper part a shelf slanting from the back downwardly 95 toward the front and provided with an opening adapted to permit the passage of a cup, and a lid hinged to the rear of the housing for covering such opening and a cup protruding through the same, of an elevator located in the housing below the said shelf 100 and adapted to carry a stack of nested cups, elevator advancing means also located below the said shelf embodying a ratchet wheel, and a pawl carried by the lid for engaging and rotating 105 the ratchet wheel.

6. In a cup dispenser, the combination with a housing provided with a hinged lid, of an elevator located therein and adapted to carry a stack of nested cups, means for advancing the elevator step by step, an 110 actuator for the elevator controlled by the raising of said lid, and means controlled by the elevator upon reaching a predetermined height for disengaging the actuator.

7. In a cup dispenser, the combination 115 with an elevator adapted to carry a stack of nested cups, of a cover for the dispenser adapted to be moved into and out of covering position between successive dispensations, elevator advancing mechanism 120 adapted to be operated by the cover in its said movements and means controlled by the elevator upon arriving at the limit of its advance for disengaging the said elevator advancing mechanism.

8. In a cup dispenser, the combination of a housing having at its upper part a shelf slanting from the back downwardly 125

toward the front and having an opening therethrough, means located in the housing for advancing the cups successively upwardly into said opening, a hinged lid on the housing, and means connected thereto for actuating the cup advancing means when said lid is operated.

Signed at New York in the county of

New York and State of New York, this 20th day of November, 1915, before two sub-
scribing witnesses.

HERMAN ELSAS.
